UNITED STATES PATENT OFFICE.

FREDERICK C. ISITT, OF RUSS, CALIFORNIA.

TRUNK-STRAP.

1,077,716.

Specification of Letters Patent.

Patented Nov. 4, 1913.

Application filed December 9, 1911. Serial No. 664,740.

To all whom it may concern:

Be it known that I, FREDERICK C. ISITT, a citizen of the United States, residing at Russ, in the county of Contra Costa and State of California, have invented certain new and useful Improvements in Trunk-Straps, of which the following is a specification.

My present invention relates to binding devices, such as trunk straps, whereby it is desired to retain portions of an article or a plurality of articles in close relation with each other.

The principal object of my invention is to provide a device whereby the strap or flexible member may be drawn and normally retained taut about an article or articles, such operation being facilitated by the combination of elements to be herein more fully set forth and claimed.

In the drawings, forming a part of this specification:—Figure 1 is a central vertical section through a trunk showing the application of my device thereto. Fig. 2 is a side elevation, of what I hereinafter term a drum device, with portions of a flexible member associated therewith. Fig. 3, is a vertical longitudinal section through the same. Fig. 4 is a sectional view on substantially the lines 4—4 of Fig. 2. Fig. 5 is a plan view of a drum used in connection with the device. Fig. 6 is a face view of an operating lever used in connection with the device. Fig. 7 is a top plan view of the device as shown in Fig. 2, on a reduced scale.

Similar characters refer to similar parts throughout the views.

As shown in the drawing, 1 designates the body of a trunk, 2 the cover thereof, which is retained in closed relation to the body, and the trunk structure embraced by a flexible member 3, such as a strap. The strap is drawn taut about the trunk structure by a drum device designated generally by 4. The drum device includes a drum 5 provided with journals 6 which have bearings in the walls 7 of a suitable casing 8 inclosing the drum. The casing 8, generally speaking, is preferably flat, and, in addition to the walls 7, includes two oppositely disposed curved walls 9, one of which is provided with a transversely extending slot 10, disposed substantially parallel to the axis of the drum 5.

Referring more particularly to the drum 5, it is further provided with an axially ex-

tending slot 11 and polygonal formed portions 12 and 13, or their equivalent, the portion 12 being complementally formed to an aperture 14 in a lever 15, by which the drum 60 may be revolved, while the portion 13 is adapted to carry with the drum, a ratchet wheel 16.

The flexible member 3 is rigidly secured to the casing 8, at 18, one of the flat portions, 65 and extends over the curved wall 9 opposite that which contains the slot 10. Inasmuch as the casing will be preferably made of rigid metal, this rounding wall avoids cutting of the flexible member should the drum 70 device 4 be placed near the edge of the trunk, or article it is associated with. And further, since articles such as trunks are roughly handled in transportation, these rounding edges avoid cutting of the flexible 75 member should some force be applied thereto to adjacent the drum device. The opposite end of the flexible member 3 from connection 18, is brought through the slot 10 and operatively connected to the drum 5, so as 80 to be wound thereupon when the drum is revolved in a certain direction. As a simple means of connection between the drum 5 and the flexible member 3, the latter may be drawn through the slot 11 in the former as 85 shown in Fig. 3 of the drawing.

The ratchet wheel 16 is so disposed as to normally resist movement of the drum 5 in a direction counter to that in which it is rotated for drawing in, or taut, the flexible 90 member 3, the ratchet wheel coacting with a pawl 19, pivoted at 20 and normally held in engagement with the ratchet wheel by a spring 21. The pawl 19 is further provided with a pin 22 extending through a slot 23 95 in one of the walls 7, to provide for its manual disengagement from the ratchet wheel.

To facilitate assemblage of the device, one wall 7 may be rigidly secured to the remainder of the casing 8 by rivet 24, while the opposite wall may be secured by the screws 25 as clearly shown in Fig. 4.

The operation of the device is as follows:—The flexible member 3 is placed about 105 the article or articles to be bound and the drum 5 is revolved to wind upon it the flexible member. As the drum revolves the pawl 19 is automatically moved from and returned to the ratchet wheel 16 preventing reverse movement of the drum 5. The revolving of the drum 5 is continued until the 110

flexible member 3 is drawn tightly about the article or articles to be bound and is retained in binding relation by the pawl 19. When the flexible member 3 is to be released the 5 drum 5 is revolved lightly forward by the lever 15 and the pawl 19 disengaged, and so held manually, until the flexible member is slack.

It will be seen that one end of the strap 10 is rigidly connected with the casing in a line coincident with the direction of the line of pull. The other end of the strap is connected with the drum in a line coincident with the line of pull. Now the casing has a relatively flat, broad bottom adapted to loosely engage the trunk and this flat, broad bottom is disposed parallel with the lines of pull in opposite directions on the strap, so that the casing is always held in a predetermined position on the trunk surface during and subsequent to the tightening operation of the mechanism in the casing. This feature not only prevents the casing from revolving or turning when the strap is being 25 tightened, but it preserves the casing in a predetermined position to preserve the disposition of the strap 10 so as to prevent the strap from buckling. It is well known that a leather strap will soon wear if it is not subjected to tension stress in the line of pull. Straps around the buckle of a trunk wear out at that point before they wear out at any other point. Now it is one of the objects of 30 my invention to prolong the life of a trunk

strap and at the same time provide a device 35 which may be completely detached from the trunk when the same is not in transport.

I claim:—

In combination, a strap adapted to be extended around an article, and a casing adapted to be loosely disposed on such article, one of the strap ends being connected with the casing and having its connected portions disposed coincident with the line of pull on the strap in one direction, strap tightening and locking mechanism in the casing, the other end of the strap being connected with said mechanism and extending toward the casing in a direction opposite to the direction of the first named end and also in a direction 45 coincident with its line of pull whereby the opposite lines of pull on the casing will tend to seat the same on such article, and devices extending exteriorly of the casing whereby the mechanism may be operated or released, 50 said casing having a broad, flat portion engaging the article and disposed in such relation with respect to the opposing lines of pull of the strap ends that the casing will be maintained in a given position during 55 and subsequent to the tightening of the strap, substantially as described.

In testimony whereof I affix my signature in presence of two witnesses.

FREDERICK C. ISITT.
